GEAR PUMP FOR ARTIFICIAL SILK SPINNING MACHINES

Otto Bochmann and Theodor Vollenbroich,
Remscheid-Lennep, Germany, assignors to
Barmer Maschinenfabrik Aktiengesellschaft,
Wuppertal-Oberbarmen, Germany

Application December 13, 1933, Serial No. 702,264
In Germany December 20, 1932

3 Claims. (Cl. 103—126)

This invention relates to a gear pump for artificial silk spinning machines, which pump serves in known manner for continually feeding a uniform quantity of the substance to be spun 5 to the spinning nozzles.

The object of the invention is to provide a connection between the driving shaft and the pump shaft which will prevent the spinning liquid from penetrating from the pump to the driving 10 shaft and end thrusts and stresses from being exerted on the pump shaft resulting in heavy wear and which at the same time enables the pump to be fitted on and removed from the spinning machine as a complete unit.

15 This is attained according to the invention in that the driving pump gear is mounted on a shaft terminating in a disc-shaped collar made in one piece with the shaft, this collar being situated in an annular groove in the cover plate, 20 which groove is closed by the support of the pump to form a narrowly restricted chamber. This arrangement presents the advantage that the pump proper forms a complete aggregate and can be removed without influencing the driving 25 shaft. The result is that the disc-shaped collar can be utilized to form a tight closure and accommodated in a narrowly restricted chamber without it being possible for end thrusts or stresses to occur between the driving shaft and the pump 30 shaft.

An embodiment of the invention is illustrated by way of example in the accompanying drawing in which:—

Fig. 1 shows the gear pump in longitudinal 35 section.

Fig. 2 is a section on line A—B of Fig. 1.

The pump, comprising a front plate 1, a middle plate 2 and a rear plate 3 is connected by screw bolts to a support 4. The gear pump is clamped 40 on the pump bridge so that the inlet passage 15 in the support communicates with the feed conduit for the spinning solution and the outlet passage 16 with the delivery conduit to the spinning nozzle. The driving shaft 13 is journalled in the support and carries on its outer end a gear, not shown in the drawing, driven by a second gear from the driving shaft of the machine. The spinning solution is fed through the passage 15 of the pump and delivered through the passage 50 16 to the spinning nozzle in uniform quantities in a certain unit of time. The middle plate accommodates two intermeshing pump gears 5 and 6 which receive the substance to be spun from the inlet passage 15 and deliver it in uniform 55 quantities through the outlet passage 16 to the

spinning nozzles. The gear 5 is mounted on a shaft 7 journalled in the front and rear plates 1 and 3 while the periphery of gear 6 provides the only journal therefor. The shaft 13 has an axial bore 14 with a widened portion of polygonal 5 cross section at its end adjacent the shaft 7. A coupling element 12 of polygonal cross-section is engaged in a polygonal bore in the shaft 7 at one end and in the widened portion of the bore in the shaft 13 at the other end and transmits the 10 rotary movement of the shaft 13 to the shaft 7, thereby driving the gears 5 and 6. To prevent the spinning solution from flowing from the pump to the driving shaft, the front plate 1 is recessed on its outer side and forms with the surface of 15 the support 4 to which it is bolted a narrowly restricted chamber in which a collar 8 formed on the outer end of the shaft 7 fits, so that the shaft 7 can rotate freely. A steel ring 9 countersunk in the support 4 bears lightly against the collar 8 20 which is consequently supported on both its faces 10 and 11 and protects the shaft 7 against end thrust and stressing.

Thus the collar 8 fitting snugly in the narrowly 25 restricted chamber formed by the plate 1 and support 4 constitutes a labyrinth packing for preventing the solution from passing to the bearing of the driving shaft 13.

A small quantity of spinning solution nevertheless leaks past this packing and is guided off 30 through the bore 14 in the shaft 13 so that it cannot reach the bearing point of this shaft.

We claim:—

1. A gear pump for artificial silk spinning machines, comprising in combination a support having an inlet and an outlet passage for the spinning solution, a casing mounted on said support and composed of an outer plate, a ring-shaped middle plate and an inner plate provided with inlet and outlet passages registering with the inlet and outlet passages in said support and communicating with the aperture in said middle plate, two intermeshing gears accommodated in the aperture in said middle plate, a pump shaft 35 carrying one of said gears, a disc-shaped collar formed on the inner end of said pump shaft, said inner plate having an annular groove accommodating said collar free from end thrusts and closed by said support to form a narrow chamber, a driving shaft journalled in said support, and an intermediate coupling element loosely connecting said driving shaft with said pump shaft.

2. A gear pump for artificial silk spinning machines, comprising in combination a support on 40

the machine frame, a cover plate bearing against said support having an annular groove closed by said support to form a narrowly restricted chamber, a middle plate, a rear plate a driving gear 5 and a driven gear in said middle plate between said cover plate and said rear plate, a shaft extending through said cover plate into said rear plate and carrying said driving gear, a disc shaped collar on the front end of said shaft fitting snugly 10 in said chamber free from end thrust, a driving shaft having a hollow inner end journaled in said support, and an intermediate element of polygonal cross section connecting said shafts, said driving shaft having a continuous longitudinal bore extending from its hollow portion to 15 its outer end.

3. A gear pump for artificial silk spinning machines, comprising in combination a support on the machine frame, a cover plate bearing against

said support having an annular groove closed by said support to form a narrowly restricted chamber, a middle plate, a rear plate, a driving gear and a driven gear in said middle plate between said cover plate and said rear plate, a shaft extending through said cover plate into said rear plate and carrying said driving gear, a disc shaped collar on the front end of said shaft fitting snugly in said chamber free from end thrust, a driving shaft having a hollow inner end 10 journaled in said support, an intermediate element of polygonal cross section connecting said shafts, said driving shaft having a continuous longitudinal bore extending from its hollow portion to its outer end, and a steel ring countersunk 15 in said support opposite said collar forming a running surface for said collar.
